UNITED STATES PATENT OFFICE.

GEORGE B. CANNON, JR., OF BROOKLYN, AND FRANK W. HOWARD, OF NEW YORK, N. Y.

UMBRELLA.

1,356,264.

Specification of Letters Patent. Patented Oct. 19, 1920.

Application filed March 22, 1919. Serial No. 284,280.

To all whom it may concern:

Be it known that we, GEORGE B. CANNON, Jr., and FRANK W. HOWARD, citizens of the United States, and residents, respectively, of Brooklyn and New York city, in the counties of Kings and New York and State of New York, have invented certain new and useful Improvements in Umbrellas, of which the following is a specification.

10 This invention relates to umbrellas and is particularly applicable to the type of umbrella which is described in copending application Ser. No. 284279. In that type of umbrella the frame is of very simple form and includes ribs that extend upwardly and outwardly from the upper end of the stick, the outer ends of the ribs being held constrained so that the cover is maintained in tension. In the present embodiment of the 15 invention the ribs are held constrained by means of stretchers. The general object of the present invention is to produce an umbrella of this type which is of very simple construction enabling it to be normally kept 20 in a folded state but so constructed that it can be readily opened out ready for use. The general purpose is to produce an umbrella that can be very economically manufactured and made available at low cost to 25 persons who have been accidentally caught in the rain.

Further objects of the invention will appear hereinafter.

The invention consists in the combination 30 of parts and simplicity of details described in the following specification all of which contribute to produce a simple, inexpensive, and efficient umbrella.

In the drawing which fully illustrates the 40 preferred embodiment of the invention,—

Figure 1 is a vertical section through the umbrella in its open condition,

Fig. 2 is a side elevation of the umbrella frame in its folded state,

45 Fig. 3 is a side elevation showing a detail of the end of a rib.

Fig. 4 is a perspective showing one of the stretchers,

Fig. 5 is a vertical section at the edge of 50 the umbrella cover and illustrating the construction of the ends of the intermediate ribs,

Fig. 6 is a plan of a corner of the umbrella,

Fig. 7 is a vertical section through an 55 umbrella showing a modification of the invention,

Fig. 7^a is a detail of the end of a stretcher,

Fig. 8 is a detail showing a modified structural relation of the ribs and stretchers, and 60

Fig. 9 is a detail showing a modified construction for securing the umbrella ribs together.

Referring more particularly to the parts, in the embodiment illustrated, the umbrella 65 comprises a stick 1 from which the ribs 2 extend. These ribs preferably extend upwardly and outwardly and may be conveniently formed as extensions of a plurality of wires 3 which are twisted together to form 70 the stick, a loop 1^a forming a handle.

These extensions or ribs 2 normally tend to assume a position extending away from the stick but parallel with the axis of the stick, see Fig. 2. This position corresponds 75 to the folded state of the umbrella. In this relation the ribs may encircle the cover 4 which may be normally rolled up in the space surrounded by the ribs. This cover is preferably formed of inexpensive water- 80 proof paper.

The outer edges of the cover are provided with eyelets 5, see Fig. 6, and the ends of the ribs are attached to these eyelets preferably by bending up the ends of the ribs to 85 form eyes 6 to engage the eyelet.

Means is provided for connecting the ends of the ribs while the umbrella is in a folded state. This means is preferably in the form of a hook 7 formed as an extension from special eyes 8. These hooks 7 may be hooked into the eyes 6 of adjacent ribs respectively. However we may form these hooks as a separate piece, 8^a attached to the end of the rib.

We provide a plurality of stretchers 9 for holding the umbrella ribs flexed. These 95 stretchers are preferably constructed so that they are detachably connected to the ribs and the stick. For this purpose the ends of each stretcher are formed with a hook or eye.

In forming the complete frame the middle portions of the stretchers are twisted down into the upper coils 12 of the stick, as at 100

11 and the hooks 10 are then applied around the stretchers, whereupon the resiliency of the ribs will cause the stretchers 10 to bend into bow form, see Fig. 1. At a certain point 5 a condition of equilibrium is reached in which the bowed stretchers hold the ribs flexed.

If it is desired to increase the flexion of the ribs, the stretchers should be detached 10 from the ribs and screwed farther down into the coils of the handle.

A modification of the invention consists in constructing the stretchers as an integral part of the wires forming part of the stick. 15 Such a construction is illustrated in Fig. 7 in which the stick 13 is constructed of coiled wires 14. At a certain point on the stick, half of the wires branch outwardly to form stretchers 15 and the remainder continue up to form the upper portion of the stick, and from the upper end of the stick these remaining wires branch outwardly and upwardly to form the umbrella ribs 16. These ribs are provided with integrally formed 20 eyes 17 into which hooks 15^a at the ends of the stretchers may be hooked.

In other respects the features of construction are the same as in the preferred embodiment of the invention.

30 Or we may use ribs without these eyes 17 and simply hook the hooks 15^a over the ribs as described in connection with Fig. 1.

Or in either embodiment of the invention we may provide a construction as in 35 Fig. 8 involving integrally formed notches or bends 18 in the ribs 19 into which the hooks 20 on the end of the stretcher 21 may engage. These notches may be used if it is desired to determine exactly the location of 40 the outer ends of the stretchers.

In both forms of the invention it will be seen that there is no direct connection between the stick and the cover of the umbrella.

45 It is understood that the embodiment of the invention described above is only one of the many embodiments or forms our invention may take, and we do not wish to be limited in the practice of our invention nor in our claims, to the particular embodiment set forth.

What we claim and desire to secure by Letters Patent is:—

50 1. In an umbrella, the combination of a stick, a plurality of ribs extending upwardly and outwardly from the stick, a cover attached to said ribs, and stretchers connecting said ribs and said stick for holding the ribs flexed.

60 2. In an umbrella, the combination of a stick, a plurality of ribs extending upwardly and outwardly from said stick, a cover having eyelets in the edge thereof, attached to the ends of said ribs, and stretchers attached at their middle points to said

stick and holding the said ribs in a flexed state.

3. In an umbrella, the combination of a stick composed of a plurality of wires with integral extensions constituting ribs of the 70 umbrella, stretchers for holding said ribs flexed, and a cover attached to said ribs.

4. In an umbrella, the combination of a stick composed of a plurality of wires twisted together, and having integral extensions 75 extending upwardly and outwardly from said stick to constitute ribs of the umbrella, stretchers connecting said stick and said ribs for holding said ribs flexed and a cover unattached to said stick and attached to said 80 ribs adjacent the ends thereof.

5. In an umbrella, the combination of a stick composed of a plurality of twisted wires, said wires having extensions constituting ribs, stretchers detachably connected to said ribs and detachably connected adjacent their middle points, to said stick, and a cover unattached to said stick and attached to said ribs adjacent their ends. 85

6. In an umbrella, the combination of a 90 stick, a plurality of wires extending from the end of the stick when the umbrella is in its closed position, so as to lie substantially parallel with the axis of said stick, said wires being resilient, and adapted to be bent 95 outwardly from said stick, to constitute ribs of the open umbrella, stretchers for detachably connecting the stick and the ribs for holding said ribs extended and a cover attached to the ends of said ribs and unattached to said stick. 100

7. In an umbrella, the combination of a 105 stick, a plurality of wires extending from the end of the stick when the umbrella is in its closed position, so as to lie substantially parallel with the axis of said stick, said wires being resilient, and adapted to be bent 110 outwardly from said stick, to constitute ribs of the open umbrella, for detachably connecting the stick and the ribs for holding said ribs extended, and a cover attached to the ends of said ribs and unattached to said stick, said ribs having eyes, and means for connecting said eyes to hold the umbrella in its folded state. 115

8. In an umbrella, the combination of a 120 stick, a plurality of wires extending from the end of the stick when the umbrella is in its closed position, so as to lie substantially parallel with the axis of said stick, said wires being resilient, and adapted to be bent 125 outwardly from said stick, to constitute ribs of the open umbrella, stretchers for detachably connecting the stick and the ribs for holding said ribs extended, and a cover attached to the ends of said ribs and unattached to said stick, said ribs having eyes and certain of said ribs having hooks for engaging the eyes on adjacent ribs respectively to hold the umbrella folded. 130

9. In an umbrella, the combination of a stick having wire coils at its upper end and extensions integral with said coils and constituting ribs, stretchers engaging said coils and retained by said coils adjacent the middle points of said stretchers, said stretchers maintaining a bowed form with their ex-

tremities engaging said ribs to maintain said ribs flexed.

Signed at New York city in the county of 10
Kings and State of New York this 18th day
of March A. D. 1919.

GEORGE B. CANNON, JR.
FRANK W. HOWARD.
